UNITED STATES PATENT OFFICE.

HENRY W. STARKWEATHER, OF NEW HAVEN, CONNECTICUT, ASSIGNOR TO WINCHESTER REPEATING ARMS CO., OF NEW HAVEN, CONNECTICUT, A CORPORATION.

ELECTRIC PRIMER.

1,034,160.

Specification of Letters Patent. Patented July 30, 1912.

Application filed April 22, 1912. Serial No. 692,366.

To all whom it may concern:

Be it known that I, HENRY W. STARKWEATHER, a citizen of the United States, residing at New Haven, in the county of New Haven and State of Connecticut, have invented a new and useful Improvement in Electric Primers; and I do hereby declare the following, when taken in connection with the accompanying drawings and the characters of reference marked thereon, to be a full, clear, and exact description of the same, and which said drawings constitute part of this application, and represent, in—

Figure 1 a view in side elevation of an electric primer constructed in accordance with my invention, shown on a greatly enlarged scale. Fig. 2 a view thereof in central longitudinal section. Fig. 3 a view of the empty primer-shell as it appears before its forward or inner end is crimped for the retention of the wad. Fig. 4 a detached view in side elevation of the contact-button. Fig. 5 a detached view in side elevation of the insulating ring for the contact-button. Fig. 6 a detached view in side elevation of the insulating spacing ring. Fig. 7 a detached edge view of the contact washer. Fig. 8 a detached view in side elevation of the container or cup. Fig. 9 a detached view of the container in central longitudinal section, showing its self-contained character, it being ready to be inserted as one piece into the container-chamber in the primer-shell. Fig. 10 a detached view in side elevation of the bridge-wire.

My invention relates to an improvement in electric primers, the object being to produce a simple and reliable primer constructed with particular reference to compactness, fewness of parts and cheapness of production.

With these ends in view, my invention consists in an electric primer having certain details of construction and combinations of parts as will be hereinafter described and pointed out in the claims.

In carrying out my invention, I produce in any approved manner a one-piece shell 2 formed with a powder-chamber 3 extending substantially throughout two-thirds of the length of the shell and designed to be filled with black or other suitable powder 4 confined by a wad 5 secured in place by crimping the extreme forward or inner end of

the shell as at 6. The rear or outer end of 55 the shell is formed with a container-chamber 7 substantially corresponding in diameter to the powder-chamber 3 and separated therefrom by a web or diaphragm 8 extending at a right angle to the longitudinal axis 60 of the shell and formed as shown, with a central, circular flash-opening 9 which provides for the passage of the igniting flame from the chamber 7 to the chamber 3. The said chamber 7 receives a flanged sheet- 65 metal cup or cup-like container 10 the crimped forward edge 11 of which rests upon the outer face of the diaphragm 8, whereby the cup is positioned in the chamber 7. 70

In assembling the several parts located within the cup or container 10, an insulating ring 12 of angular cross-section is placed in the bottom of the said cup so as to rest upon the annular flange 13 at the outer end 75 thereof, the collar 14 of the said ring 12 fitting snugly within the opening 15 within the flange 13 of the cup. A flanged contact-button 16 is then introduced into the cup 10 together with the platinum ignition 80 or bridge-wire 17 the outer end of which is hooked over the flange 18 of the button, the main or body portion of which extends rearward through the collar 14 aforesaid of the insulating ring 12. The contact-button 16 85 and bridge-wire 17 having been positioned in the cup, the insulating spacing-ring 19 is set into the cup so as to rest upon the forward face of the said contact-button. The outer end of the bridge-wire 17 is then 90 brought forward to rest upon the forward face of the ring 19 after which the contact-washer 20 is set within the cup 10 so as to rest upon the outer end of the bridge-wire 17 and hold the same in place as shown in 95 Fig. 2 in which the wire is seen to extend diagonally across the space inclosed by the insulating spacing ring 19. The edge of the cup 10 is now crimped as at 11 to retain the contact-washer 20 in place. The space inclosed by the ring 19 and contact-washer 20 100 is now filled with gun-cotton 21. It will be understood that the several parts are assembled within the cup or container 10 prior to its introduction into the chamber 7 105 in the shell 2.

In using the primer the current is transferred from the firing mechanism of the

gun to the contact-button 16 from which the current passes through the bridge-wire 17 to the contact-washer 20 from which the current passes to the cup or container 10, 5 and thence to the primer-shell 2. The passage of the current through the wire 17 heats the same to incandescence and ignites the gun-cotton 21, the flame of which leaps forward through the flash-opening 9 into 10 the powder-chamber 3 containing the powder 4, the ignition of which ignites the charge, whatever it may be, in the shell in which the primer is used.

Instead of forming the diaphragm 8 with 15 a single central flash-opening, it might be formed with several flash-openings; so, too, if preferred, two or more bridge-wires might be employed instead of a single bridge-wire. These changes are thought to 20 be too obvious to call for illustration or further description.

It will be observed that the container 10 is, so to speak, self-contained in so far as it is entirely assembled with all of its parts 25 prior to its introduction into the container-chamber 7 in the primer-shell 2. The container having received its contents is handled as one piece, and as such is introduced into the container-chamber in the 30 primer-shell without any reference to the powder-chamber of the shell or the contents thereof. By my improvement the cost of assembling the primer-shell is thus greatly reduced, the shells and container being 35 made and assembled in quantities, whereas in the prior practice most of the parts connected with the function of ignition have been applied one by one.

I claim:—

- 40 1. A one-piece electric primer-shell formed with a powder-chamber and a container-chamber substantially corresponding to each other in diameter and separated by a diaphragm arranged at a right angle to the longitudinal axis of the said shell and substantially corresponding in thickness thereto, and formed with a flash-opening.
- 45 2. A self-contained container for use in electric primers, the said container consisting of a sheet metal cup formed at its outer end with an inwardly turned annular flange, and the said cup containing a contact-button retained in place by the said flange, an insulating ring inclosing the said button, a bridge or ignition wire located within the said ring, and combustible material to be ignited by the said wire, located

within the said ring in front of the said button.

3. In an electric primer, the combination 60 with a primer-shell formed with a powder-chamber and a container-chamber connected by a flash-opening, of a self-contained container adapted to be introduced into the container-chamber without reference to the 65 powder-chamber and containing a contact-button, insulating material, an ignition wire, and combustible material to be ignited by the said wire.

4. In an electric primer, the combination 70 with a one-piece primer-shell formed with a powder-chamber and a container-chamber separated from each other by a diaphragm having a flash-opening; of a self-contained container adapted to fit within the said 75 container-chamber, and an insulating ring, a contact-button, a bridge-wire, and a contact-washer, all located in the said container.

5. In an electric primer, the combination 80 with a primer shell formed with a powder-chamber and a container-chamber; of a container located within the said container-chamber, and a contact-button, bridge-wire, contact-washer, and insulating members located within the said container, whereby the contact-button and bridge-wire are insulated therefrom.

6. In an electric primer, the combination 90 with a primer-shell formed with a powder-chamber and a container-chamber separated by a diaphragm containing a flash-opening; of a cup-like container located within the 95 said container-chamber, a flanged insulating-ring located within the outer end of the 100 said container, a flanged contact-button located within the said ring, an insulating spacing-ring located within the container and bearing upon the said contact-button, a contact-washer located within the 105 container and bearing upon the forward face of the insulating spacing-ring, and a bridge-wire extending between the contact-button and spacing-ring and into the space within the spacing-ring which is filled with gun-cotton and located in line with the flash-opening aforesaid.

In testimony whereof, I have signed this specification in the presence of two subscribing witnesses.

HENRY W. STARKWEATHER.
